CARBURETOR

Eldred A. Switzer, Vancouver, British Columbia,
Canada

Application April 16, 1945, Serial No. 588,429

6 Claims. (Cl. 48—180)

1

This invention relates to an improved carburetor for internal combustion engines.

It is an object of the present invention to provide a carburetor comprising adjustable automatic means, operated by the degree of suction in the mixing chamber, for controlling the ratio of fuel to air in the mixture.

It is also an object of the present invention to provide an improved carburetor in which means are provided for vaporizing the fuel before admission to the mixing chamber, thus eliminating need for a float chamber, and improving the thermo-dynamic qualities of the resulting mixture to provide more efficient combustion.

It is a further object of the invention to provide adjustable automatic means for maintaining substantially constant the temperature of the vaporized fuel supplied to the mixing chamber.

Other features and objects of the invention will appear from the following description with reference to the accompanying drawings, in which:

Fig. 1 is a cross sectional view of a carburetor according to the invention taken on the line 1—1 in Fig. 2, and

Fig. 2 is a sectional plan view taken on the line 2—2 in Fig. 1.

The carburetor unit shown in the drawings consists basically of a mixing chamber 10 and a vaporizing unit 11. Vaporized fuel is fed from the latter to the mixing chamber by means of fuel supply line 12 and fuel inlet tube 13 suitably mounted in the walls of the mixing chamber and extending centrally across it (see Fig. 2). The escape of vaporized fuel from tube 13 is effected through a suitable orifice 14, and is controlled by a metering pin 15 carried by a stem 16 the lower end of which extends through a suitable hole in a guide bar 17 mounted in the walls of the mixing chamber below the usual Venturi throat 18. A spring 19 urges the metering pin upwardly to close the orifice 14 at its upper or reduced end. Pin 15 is provided with an extension 20 guided in a bore 21 formed in a guide member 22 suitably mounted on fuel inlet tube 13.

At its lower end the mixing chamber 10 is provided with a flanged portion 23 for attachment to a butterfly valve unit partially shown as 24 in Fig. 1, this unit containing the usual throttle valve leading to the intake manifold.

At its upper end the mixing chamber is provided with a perforated cap 25 having perforations 26 to allow for each ingress of air. Passing through the perforated cap is a valve stem 27 on which is mounted an air inlet valve 28 adapted

2

to be moved downwardly against spring 29 to admit air to the mixing chamber when suction is created therein. The lower end of the valve stem 27 is supported by a tubular guide sleeve 30 fitted over the guide member 22, and, like it, suitably mounted on the tube 13. At its lower end the guide sleeve 30 is provided with a flange 31 retaining spring 29 the other end of which bears against the lower face of the air inlet valve 28 urging it to the seated position shown in Fig. 1.

The air inlet valve 28 is disc-shaped, and has extending through it a plurality of holes 32 which are covered by an auxiliary disc 33 normally held in contact with the top surface of the valve member 28 to close the holes 32, by a relatively weak spring 34. The disc 33 which is mounted to slide on the stem 27 normally rides up and down with the valve 28 and stem 27, but on occurrence of a sudden increase in pressure in the mixing chamber, such as might be caused by a backfire, the disc 33 is forced upwardly away from valve 28, thereby clearing the holes 32 and allowing the gases to escape harmlessly there-through.

The air inlet valve 28 is connected to the metering pin 15 so that the latter is operated to admit vaporized fuel to the mixing chamber through orifice 14 in a proportion dependent on the volume of air admitted by the valve 28, the connection being as follows: An arm 35 having arcuate top and bottom surface is pivoted at 36 at one side of the mixing chamber, and extends across the chamber as appears from Fig. 2. Near to the end which is opposite to the pivot 36 the top surface of the arm 35 is engaged by a follower member 37 connected to valve member 28 to move up and down with it and to pivot the arm 35 downward accordingly. The lower arcuate face of the arm 35 is engaged by a second follower 38 which is slidable from end to end of the lower arcuate surface and is connected to shoulder 39 of metering pin 15 by means of link 40 pivotally connected to such shoulder at 41. The follower 38 is adjusted along the length of the lower arcuate surface of the arm 35 by means of a manual control cable 42 which projects through a packing gland 43 shown in dotted lines in Figure 2.

It will be observed that as pressure is reduced in the mixing chamber, and thus the air inlet valve 28 is moved downwardly, the metering pin 15 is moved away from its seating in the orifice 14 in order to admit vaporized fuel to the mixing chamber in proportion to air admitted by open-

ing of the valve 28. It will be further observed that the relationship between the opening of the orifice 14 and the opening of the air valve 28, and thus the fuel air ratio, may be varied by adjusting the position of the follower 38 along the lower arcuate surface of the arm 35. Thus if the follower 38 be positioned at the extreme left end of arm 35, that is, at the opposite end of the position shown in Figure 1, downward movement of air inlet valve 28 causes relatively little movement of the metering pin 15 and thus relatively little opening of the orifice 14. In Fig. 1 the follower 38 is shown in a position which would cause maximum movement of the metering pin 15 for a given movement of the air inlet valve 28, this resulting in a maximum obtainable fuel air ratio in the combustion mixture.

The vaporizing unit 11 consists of a double helical coil 44 made of fuel line tubing and connected in the fuel line supplied by the conventional fuel pump (not shown). The outer helical coil is connected to the supply line from the fuel pump at 45 and is connected in the line 12 leading to the tube 13 at 46.

The vaporizing unit 11 is provided with a base 47 rigidly connected to the mixing chamber 16 by screws 48. The base 47 is provided with an inlet port 49 suitably connected to be supplied with exhaust gases from the exhaust manifold of the internal combustion engine, and an exhaust port 50. The outer wall of the vaporizing unit is formed by a tubular cover member 51 supported on the base 47 and closed at the top by a cap 52. Also mounted on the base 47 is an inner tube 53 which fits within the outer helix of coil 44 and around the inner helix. This inner tube 53 has a perforated cap 54, and both of the tubes 51 and 53 are held in position on the base 47 by means of their respective caps 52 and 54. The inner cap 54 is engaged by flange 55 of rod 56 screwed into base 47 at 57, and the outer cap 52 is held in position by screw 58 screwed into the end of rod 56. It will be seen that the members 51 and 53 with their caps 52 and 54 can be readily removed for inspection and cleaning purposes.

The exhaust gases on entering port 49 follow a course indicated by the arrows A and B up around the inner helix of tube 44 within the member 53, through the perforations in the cap 54, downwardly as indicated by the arrows B in the space between the members 51 and 53 and thus around the outer helix of the coil 44 and out the exhaust port 59. It will be observed that this arrangement provides that the hottest (that is the freshest) exhaust gases first come in contact with that part of the helical coil 44 which contains fuel about to be delivered to the inlet tube 13 in the mixing chamber. It follows that fuel entering the vaporizing units from the fuel pump comes in contact with hotter gases as it progresses, and therefore is heated gradually and rapidly. In this manner it is insured that maximum effectiveness is obtained from the exhaust gases.

Mounted on the outside of the cover member 51 is a thermostat 59 which is connected to a butterfly valve (not shown) which regulates the supply of exhaust gases to port 49. This thermostat is adjustable and can be adjusted to keep the vaporized fuel supplied to the mixing chamber 16 at a constant optimum temperature. The importance of this thermostatic control is realized when it is considered that since the fuel in the fuel inlet tube 13 is in a vaporized condition, according to the laws of gases any change in its

temperature will cause a change in its pressure. This causes variations in the amount (by weight) of the fuel supplied to the mixing chamber 16 upon a given movement of the metering pin 15 and the air inlet valve 28 (the greater the fuel pressure, the greater being the amount of vaporized fuel admitted to the mixing chamber). This in turn causes a variation in the mixture and a corresponding loss in thermodynamic efficiency in the combustion. The provision of the thermostatic control eliminates the possibility of such variations of mixture by keeping the temperature, and therefore the amount of the vaporized fuel supplied substantially constant for any given degree of suction in the mixing chamber.

What I claim is:

1. A carburetor for internal combustion engines comprising a mixing chamber, an air inlet valve for said chamber adapted to be opened in response to reductions in pressure within said chamber, spring means urging said valve into the closed position, means supplying vaporized fuel to said mixing chamber, metering means controlling admission of said vaporized fuel, and adjustable means connecting said air inlet valve to said metering means to operate the latter according to opening of said air inlet valve to admit vaporized fuel to said mixing chamber in proportion to the admission of air thereto, said adjustable means connecting said air inlet valve and metering means comprising an arcuate member pivoted at one end at one side of said mixing chamber and engaged adjacent the other end by means in connection with said air inlet valve adapted to move said arcuate member towards said metering means on opening of said air valve, a follower member movable from one end to the other of said arcuate member and movable towards said metering means by said arcuate member, means for adjusting the position of said follower along the length of said arcuate member and means connecting said follower to said metering means, said metering means being actuated on opening of said air inlet valve to a degree determined by the adjustment of said follower member along the length of said arcuate member.

2. A carburetor for internal combustion engines comprising a mixing chamber, an air inlet valve for said chamber adapted to be opened in response to reductions in pressure within said chamber, spring means urging said valve into the closed position, means supplying vaporized fuel to said mixing chamber, metering means controlling admission of said vaporized fuel, and adjustable means connecting said air inlet valve to said metering means to operate the latter according to opening of said air inlet valve to admit vaporized fuel to said mixing chamber in proportion to the admission of air thereto, said means for supplying vaporized fuel to said mixing chamber comprising a housing, a fuel supply line, a double helical coil in said housing connected in said fuel line, and means supplying heat to said double helical coil, and said adjustable means connecting said air inlet valve and metering means comprising an arcuate member pivoted at one end at one side of said mixing chamber and engaged adjacent the other end by means in connection with said air inlet valve adapted to move said arcuate member towards said metering means on opening of said air valve, a follower member movable from one end to the other of said arcuate member and movable towards said metering means by said arcuate member, means for adjusting the position of said

follower along the length of said arcuate member and means connecting said follower to said metering means, said metering means being actuated on opening of said air inlet valve to a degree determined by the adjustment of said follower member along the length of said arcuate member.

3. A carburetor for internal combustion engines comprising a mixing chamber, an air inlet valve for said chamber adapted to be opened in response to reductions in pressure within said chamber, spring means urging said valve into the closed position, means supplying vaporized fuel to said mixing chamber, metering means controlling admission of said vaporized fuel, and adjustable means connecting said air inlet valve to said metering means to operate the latter according to opening of said air inlet valve to admit vaporized fuel to said mixing chamber in proportion to the admission of air thereto, said means for supplying vaporized fuel to said mixing chamber comprising a housing, a fuel supply line, a double helical coil in said housing connected in said fuel line, and means for supplying hot gases to said housing and circulating the same therethrough around said double helical coils, and said adjustable means connecting said air inlet valve and metering means comprising an arcuate member pivoted at one end at one side of said mixing chamber and engaged adjacent the other end by means in connection with said air inlet valve adapted to move said arcuate member towards said metering means on opening of said air valve, a follower member movable from one end to the other of said arcuate member and movable towards said metering means by said arcuate member, means for adjusting the position of said follower along the length of said arcuate member, and means connecting said follower to said metering means, said metering means being actuated on opening of said air inlet valve to a degree determined by the adjustment of said follower member along the length of said arcuate member.

4. A carburetor for internal combustion engines comprising a mixing chamber, an air inlet valve for said chamber adapted to be opened in response to reductions in pressure within said chamber, spring means urging said valve into the closed position, means supplying vaporized fuel to said mixing chamber, metering means controlling admission of said vaporized fuel, and adjustable means connecting said air inlet valve to said metering means to operate the latter according to opening of said air inlet valve to admit vaporized fuel to said mixing chamber in proportion to the admission of air thereto, said means for supplying vaporized fuel to said mixing chamber comprising a housing, a fuel supply line, a double helical coil in said housing connected in said fuel line, means for supplying heat to said double helical coil, and a thermostatic control device adapted to maintain the vaporized fuel supplied to said mixing chamber at a substantially constant temperature.

5. A carburetor for internal combustion engines comprising a mixing chamber, an air inlet valve for said chamber adapted to be opened in response to reductions in pressure within said chamber, spring means urging said valve into the closed position, means supplying vaporized fuel to said mixing chamber, metering means controlling admission of said vaporized fuel, and adjustable means connecting said air inlet valve

to said metering means to operate the latter according to opening of said air inlet valve to admit vaporized fuel to said mixing chamber in proportion to the admission of air thereto, said means for supplying vaporized fuel to said mixing chamber comprising a housing, a fuel supply line, a double helical coil in said housing connected in said fuel line, means for supplying heat to said double helical coil, and a thermostatic control device adapted to maintain the vaporized fuel supplied to said mixing chamber at a substantially constant temperature, and said adjustable means connecting said air inlet valve and metering means comprising an arcuate member pivoted at one end at one side of said mixing chamber and engaged adjacent the other end by means in connection with said air inlet valve adapted to move said arcuate member towards said metering means on opening of said air valve, a follower member movable from one end to the other of said arcuate member and movable towards said metering means by said arcuate member, means for adjusting the position of said follower along the length of said arcuate member, and means connecting said follower to said metering means, said metering means being actuated on opening of said air inlet valve to a degree determined by the adjustment of said follower member along the length of said arcuate member.

6. A carburetor for internal combustion engines comprising a mixing chamber, an air inlet valve for said chamber adapted to be opened in response to reductions in pressure within said chamber, spring means urging said valve into the closed position, said valve having at least one hole extending therethrough, an auxiliary valve disc on the outer surface of the inlet valve normally covering the hole therein, spring means normally holding the valves together, said auxiliary valve disc being adapted to uncover the hole on sudden increase of pressure in the chamber, means supplying vaporized fuel to the mixing chamber, metering means controlling admission of the vaporized fuel, and adjustable means connecting said air inlet valve to said metering means to operate the latter according to opening of said air inlet valve to admit vaporized fuel to said mixing chamber in proportion to the admission of air thereto.
